METHOD OF AND APPARATUS FOR COOLING ENGINES

Filed July 16, 1928

UNITED STATES PATENT OFFICE

CLINTON R. FOUTZ, OF BALTIMORE, MARYLAND

METHOD OF AND APPARATUS FOR COOLING ENGINES

Application filed July 16, 1928. Serial No. 292,991.

This invention is directed to a method of and means for utilizing and governing the cooling medium of a cooling system for internal combustion engines.

- 5 In cooling systems of this type as at present constructed, the cooling medium, usually water, is circulated between an air-cooled container, as the conventional radiator, and the engine walls or other parts to be cooled. 55
10 During this circulation, heat is extracted from the parts to be cooled by the cooling medium and such heat dissipated by the transfer of its heat and consequent reduction of the temperature of the cooling medium in 60
15 the radiator. Such systems are generally, if not invariably, provided with an atmospheric vent through which the system is freely open at all times to the free admission of air and to the free escape of any vapor generated 65
20 by the cooling medium in its heated condition.

Cooling systems of this accepted type labor under well recognized and material disadvantages. Primarily, the inherent quality of the cooling medium for maximum heat 70
25 extraction in the initial operation of the engine; the comparatively slight heat dissipation during the circulation of the medium; the failure of such medium to dissipate the extracted heat in accordance with the heat 75
30 degree of the parts being cooled; and the circulation of the cooling medium in a highly heated condition during the operation of the engine with a consequent failure of such medium to effectively reach the hottest part to 80
35 be cooled.

As a result of these disadvantages, an appreciable period is required to warm up the engine to an effective working temperature for the reason that the circulating cooling 85
40 medium, being at this time at the minimum temperature and maximum density, rapidly extracts the heat developed in the operation of the engine and hence compels the engine to heat the cooling medium to a very appreciable degree before being permitted to retain that heat necessary to bring the engine to an efficient working temperature. The other disadvantages tend to an ineffective maintenance of a proper working temperature for the engine during operation, for 90
45
50

there is absolutely no relation between the heat dissipation of the cooling medium and the temperature of the engine parts to provide that proportional heat dissipation which will maintain the engine at the proper working temperature under all operating conditions, and furthermore the circulation of the cooling medium in a substantially highly heated condition during the operation of the engine tends to the formation of this highly heated cooling medium into more or less vaporous condition, at least in part, through the mechanical operation of the impeller blades of the pump, with the result that within the water jacket of the engine and at the point of highest heat therein there is a collection of vaporous or gaseous particles incident to the vaporization of the cooling medium, the comparatively low specific heat of which precludes even that degree of heat 95

The present invention is directed to a method of cooling involving primarily two stages, in one of which, referred to as the aerated stage, the cooling medium is charged with an excess volume of air to provide an air and water emulsion to reduce the specific heat of the cooling medium as an entirety; and in the other of which, known as the de-aerated stage, the air is detrained from the cooling medium with the result of changing the essential characteristic of the cooling medium with the effect of materially raising its 100

boiling point without, however, interfering with its normal vaporization point.

In connection with the aerated stage, the invention further consists in a method of automatically providing an air and water emulsion, circulating such emulsion in contact with the parts to be cooled to thereby reduce the heat extraction in a given length of time as compared with the heat extraction 10 capacity of the normal cooling medium; providing for the collection of the air entrained by the system as well as the natural air content of the fluid in a confined area on the surface of the cooling medium to utilize the 15 pressure of such air in its heated condition to prevent initial vaporization of the cooling medium, and finally to detrain and automatically expel the air from the system to thereby change the physical state of the cooling medium to raise the ebullition or boiling point 20 of such medium without interfering with its vaporization point.

In connection with the deaerated stage, the invention also consists in a method of 25 affecting the circulation of the heating medium under the pressure of its own saturated vapor to thereby govern the rate of heat dissipation in direct accordance with the temperature of the parts to be cooled.

30 A further method of the invention in connection with the deaerated stage is to control the pressure head of the cooling medium, that is, the pressure of the saturated vapor, by a suction force proportioned to the circulation 35 and thereby directly controlled by the engine speed, whereby the circulatory flow of the cooling medium is affected by a variable pressure head.

To illustrate the application of and means 40 for carrying out the method of the improved invention, reference may be had to the accompanying drawings, wherein:

Figure 1 represents, in elevation and partly in section, a construction of the conventional cooling system apparatus modified in accordance with the present invention.

Figure 2 is a broken sectional view of a modification.

In this illustration, 1 indicates the engine 50 water jacket, 2 the upper water manifold, 3 the radiator, 4 the condenser, 5 the condensate tube leading from the lower tank of the condenser through a non-return valve 6 to the Venturi suction device 7 arranged in 55 the lower connection 8 leading from the radiator to a driven pump 9, with the latter having the usual connection 10 with the water jacket. 14 indicates the vapor chamber above the surface of the cooling medium in the 60 radiator which, in the form shown, has a restricted or controllable communication with the lower tank 17 of the condenser. A pipe or outlet 21 has open communication with the vapor chamber 14 and leads therefrom 65 through an adjustable outlet valve 11 having

an atmospheric vent 12, a baffle 13 protecting the inlet end of the pipe 21. A water level gauge 18 may be and preferably is connected by pipes 19 and 20 with the respective ends of the radiator in order that the level of water therein may be indicated. A radiator 70 filling opening is indicated at 22 having a cap 23 which may be applied in sealing relation.

Assuming that the radiator 3 has been filled to a desired level above the combustion chamber, as to the line W as may be indicated by the gauge, the filler cap 23 is secured in place to seal the inlet against air admission or vapor escape. When the engine is started, the pump 9 induces circulation which, as the cooling medium flows through the Venturi tube 7, establishes at the nozzle of the condensate tube 5 a differential pressure or dynamic suction which is at all times greater than at any other point in the cooling system. The suction thus created is transmitted through the non-return valve 6 and condensate tube 5 to the lower tank 17 and condenser 4 and through the restricted opening between said tank and the vapor chamber 14, with the effect to draw the air originally contained in said vapor chamber at the starting of the engine to and mix the same with the water or cooling medium. This air is cavitated by the impeller blades of the pump forming an intimate emulsion of water and air, the specific heat of which emulsion is lower than that of the water. As the engine continues to run and heats up, it is apparent that, owing to the increased temperature of the circulating medium, both the soluble and emulsified air in continually increasing quantity, is separated from the water and tends to collect in the vapor chamber.

The safety valve 11, which is a temperature control valve so far as its adjustment is concerned, may be set for relief at, say, 220° F. and at this temperature will permit the detrained air and a small amount of vapor to escape through the vent 12.

Up to the expulsion of air, the system is acting under its aerated stage and in this stage has a very material and important advantage in connection with the operation of the engine. As the air and water emulsion has a less specific heat than that of the water alone, it is apparent that during the operation of the system under this aerated stage, a given volume of the heat absorptive capacity of the air and water emulsion will extract less heat from the cylinder walls in a given time than would the same volume of water alone. That is to say, the heat generated in the operation of the engine is to a greater extent retained by the engine walls during the circulation of the air and water emulsion than would be possible under the circulation of the water alone. Therefore, the engine heats up more rapidly and more uniformly than would otherwise be the case, with the effect to bring the engine to 130

a proper working temperature in a very materially less period of time than where water is circulated alone, as in the conventional systems. Furthermore, the collection of the 5 detrained air in the vapor chamber, by reason of the pressure incident to the heated condition of such air, tends to prevent the rapid formation of vapor from the water content and to this extent, by preventing heat dissipation 10 incident to the formation of such vapor, tends to further reduce the warming up period of the engine.

Following the expulsion of the air, the system is then in what is known as the deaerated 15 stage, during the functioning of which, as the temperature of the circulating water increases, the vapor in the vapor chamber will correspondingly increase.

As a prelude to the operation of the system 20 in this deaerated stage, it is to be understood that the term "vaporization" as used herein is to be defined as the passage of a liquid into a gaseous state, that the term "evaporation" as used herein is to be defined as the slow production 25 of vapor at the free surface of the liquid, and that the term "boiling" or "ebullition" as used herein is to be defined as the rapid production of vapor in the mass of the liquid.

30 It is further assumed, as a result of numerous experiments, that as the result of the deaeration of the water at constant pressure and high temperature, a physical state of that fluid is produced which is different from the 35 fluid under normal atmospheric conditions. This may be briefly stated that by the removal of the soluble air gases, the molecular cohesion between the water particles is increased with the effect to prevent ebullition 40 or boiling except at a temperature materially above that of the liquid under normal atmospheric conditions. It is to be particularly noted here that, while this change in the physical state of the fluid due to deaeration 45 materially raises the boiling point of that fluid, it does not, however, interfere with the vaporization point of the fluid other than to increase such rate in proportion to the increased temperature.

50 As the system continues to operate in a deaerated stage, it will be apparent that in the vaporization of the water incident to the heat extracted from the walls of the cylinder vapor collects in the vapor chamber 14, the 5 amount of saturated vapor given off by the water being dependent upon the temperature of the latter. This saturated vapor condensed by the cooling influence of the condenser 4 is drawn as a liquid through the 10 condensate tube 5. If the condenser is ineffective for any reason, the condensate tube 5 will draw the saturated vapor as such to the Venturi tube where it would be condensed by the cooler fluid, past the non-return 55 check valve 6 and returned through the

circulatory path of the water by reason of the suction in the Venturi tube 7.

It is apparent that the dynamic suction effect of the Venturi tube varies with the speed of the engine and it is through this control 70 that the present system presents a balanced operation. That is to say, as more heat is rejected to and absorbed by the water with increased engine speed, a greater dynamic suction is applied to the condenser, increasing 75 the heat dissipation. The enforced condensation thus created prevents the steam pressure on the surface of the liquid from increasing by reducing the saturated vapor volume to a liquid. Therefore, as its volume 80 is not permitted to increase, the temperature cannot increase.

The heat dissipation from the cooling medium is obtained from the dissipation to the air from the cooling effect of the radiator and of the condenser in the act of condensing. The temperature of the cooling medium before entering the engine jacket being further reduced by and through the sensible 85 heat of the cold condensate returned as liquid 90 to the circulating medium.

In order to maintain a heat dissipation balanced with relation to and maintained in proportion with the speed of the engine, it is apparent that the system must automatically 95 take care of the return of the condensate to the circulating medium, that is, the withdrawal of saturated vapors from the surface of the cooling medium in substantial proportion 100 to the generation of such vapors or in the absence of a complete balance of this condensation and vapor pressure, utilize the latter to indirectly affect the circulatory speed of the cooling medium and increase 105 the vapor entering the condenser to thereby vary the heat extraction. In the present system this balance is maintained, and as the variables involved in the balancing are direct products of the engine speed, it is apparent 110 that by the system, the speed of the engine is practically the automatic controlling factor in the heat dissipation. Therefore, it is possible with the proper regulation 115 of the details of the system, to maintain the engine at a proper working temperature without any regard to its speed, for the speed of the engine is utilized as a means for automatically controlling the heat dissipation in accordance with that speed and if the fixed 120 details of the system are arranged to provide for this heat dissipation beyond a certain desired temperature of the engine and the heat dissipation is automatically controlled in accordance with all variations beyond this predetermined heat, the ideal operating conditions are maintained without regard to engine speed.

For an understanding of this automatic regulation, several factors must be borne in mind. In the first place, the vaporization of 125

the cooling medium is proportional to the temperature of that medium, and exposition of new free surface by turbulent flow of the discharge into the radiator, naturally increasing with the heat of the medium. The suction at the Venturi tube is dependent upon engine speeds, increasing rapidly with the increased speed of the engine. The presence or absence of vapor pressure in the vapor chamber 14 indirectly effects rapidity of circulation of the cooling medium.

As the vapor increases in the vapor chamber incident to increased heat of the cooling medium resulting from an increased speed of the engine, the suction at the Venturi tube naturally increases and a greater quantity of condensate is returned to the cooling medium. If the action of the Venturi tube balances the vaporization, the circulation of the cooling medium is incident to the operation of the pump and if this balance is maintained there is of course a substantially constant heat condition of the cylinder walls. If, on the other hand, the increased engine speed tends to an increase in the temperature of the cooling medium and a consequent vapor generation in excess of that which can be taken care of by the suction of the Venturi tube, the vapor generation in the chamber 14 increases with the effect to build up a pressure on the surface of the cooling medium with the result of indirectly accelerating the flow of the circulating medium to the pump on its suction side to decrease the liability of cavitation and, therefore, assist in maintaining the volume of circulation. This of course results in increased heat extraction from the cylinder walls, increased dissipation of that heat by increased vaporization, and a consequent compensation for the otherwise increased heat of the engine and maintains the engine at the predetermined working temperature. However, if the dynamic suction of the Venturi tube is sufficient to produce a sub-atmospheric condition in the vapor chamber, it is apparent that there is a suction at the fluid surface with the effect of correspondingly decreasing the circulatory rate, retarding the heat extracted from the cylinder walls and heat dissipation and avoiding reducing the heat of the cylinder walls below that predetermined operating temperature desired.

It will thus be apparent that the circulatory rate or fluid flow of the cooling medium is influenced by the variable pressure head above its surface and that this pressure head is controlled by a variable suction which is created by the rate of flow or velocity of the cooling medium below its surface.

The system, therefore, in the particulars so far described, provides for a heat dissipation which may be regulated to meet full or light load conditions of the engine and in its regulation maintain approximately the same ef-

ficient engine temperature, thereby permitting the engine to operate under all load conditions at its most efficient working temperature.

It is of course to be understood that the present system is closed against the admission of air, and while air is freely ejected past the safety valve, which also relieves pressure conditions of the steam at the temperature for which the valve is set, air cannot re-enter the system. It is of course appreciated that it is practically impossible to maintain the system against air admission, for with the numerous joints and connections required, air leakage to a slight extent is probably inevitable. Even assuming that some air is admitted under these adverse mechanical conditions, it will be apparent that such air, after initial deaeration of the system, can have but little effect upon the system for it will be detrained from the cooling medium and ejected exactly as in the initial operation. As such casually admitted air incident to mechanical defects is not considered as in any way effecting the cooling medium in the manner in which said medium would be effected if open to the atmospheric conditions under the present type of vented systems, it will be understood that the present system is one in which admission of air is precluded, that is, the system so far as its functioning and operation is concerned is completely closed against the admission of air.

It will be appreciated that under certain conditions of operation there will be a sub-atmospheric condition in the vapor chamber 14. For example, such a sub-atmospheric condition will exist when a considerable cooling of the circulating medium has occurred through the standing of the engine for a considerable period with the engine stopped following initial deaeration of the system. If, under these conditions, the engine is started, there will be a sub-atmospheric condition on the surface of the cooling medium with the effect to cause the cooling medium to boil at the point of contact with the cylinder walls by the heat of the engine, that the reduction of pressure, now necessary to form gas bubbles within the mass. This condition of sub-atmospheric boiling tends to the creation of an infinite number of vapor bubbles next the surface of the heating cylinder walls which tend, by reason of their character, to constitute in a measure a heat insulating medium between the cylinder wall and the liquid. The heat insulation of course is due to the less specific heat of the vapor than of the water and this lowering of the specific heat tends to a less heat extraction from the cylinder walls. Furthermore, at this time there is an appreciable suction on the surface of the cooling medium which, as previously explained, tends to a retardation of the circulatory rate of flow.

By reason of these combined effects, even under sub-atmospheric conditions in the vapor chamber, the heat of the cylinder walls will be permitted to build up to a proper 5 working engine temperature before the circulating fluid reaches its normal temperature of operation. This sub-atmospheric boiling at the cylinder walls tends to a rapid increase of vapor in the vapor chamber, in- 10 creasing the pressure on the circulating medium to raise the boiling point of such medium until finally the system is balanced as previously described, the sub-atmospheric condition is corrected, vaporization to an ex- 15 treme degree at the cylinder walls is imme- diately checked and ceases, and the system again acts in a normal balanced condition, dissipating the heat in accordance with the generation of that heat and maintaining the 20 engine at the normal operating temperature.

The system has the further inherent ad- vantage of providing for the maintenance of the cylinder walls at practically any tem- 25 perature up to the limit developed by the heat of the fuel charge under combustion with the effect of avoiding heat loss by con- duction through the cylinder walls and thereby utilizing a materially increased 30 number of heat units in work in the cylinder. To provide for maintaining an increased 35 heat condition in the cylinder as compared with the heat condition of the cylinder under the conventional cooling systems, the circulation of the cooling medium of the present system must be retarded and this may be readily accomplished by the provision of a valve 25 adjacent the radiator outlet, as in- 40 dicated in Figure 2 of the drawings.

Under this retarded circulatory flow, the 45 cooling medium in its initial circulation, re- maining longer in contact with the cylinder walls and absorbing that proportion of the heat passing through them, results in a rapid heating of the cooling medium and in 50 effect extreme vaporization of such medium throughout the wetted area of the combus- tion chamber, walls and circulated parts. This vapor collects in the vapor chamber 14, exerting a continually increasing pressure 55 on the surface of the cooling medium with the natural effect of preventing a boiling of such cooling medium at the surface. This increased pressure in the vapor chamber is not withdrawn therefrom in proportion to 60 its creation through the Venturi suction, for this volume has now been reduced due to the rate of reduction in the circulatory flow of the medium by the valve 25. The cooling medium will thus be rapidly heated to a high 65 degree, and as its temperature approaches that of the internal temperature of the cylinder, the cooling medium will extract corre- spondingly less heat from the cylinder walls until at the desired condition a comparative- ly small amount of the interior heat of the

cylinder will be conducted through the walls to the cooling medium. That is to say, the temperature of the cooling medium will nearly approach that of the internal heat of the cylinder, so that said internal heat can be 70 conserved for work within the cylinder instead of being transferred to and dissipated by the cooling medium as in the conventional system. Naturally a condition of this char- 75 acter raises the temperature of the cooling medium very materially above that of its boiling point, even considering such boiling point in excess of its normal boiling point due to the molecular change in the cooling medium of the present system incident to its 80 deareated condition. However, as the tem- perature of the cooling medium is raised, the pressure in the vapor chamber 14 corre- spondingly increases, and following the nat- 85 ural law this increase of pressure on the sur- face of the cooling medium prevents any tendency to boiling.

A proportional quantity of the saturated vapor in the vapor chamber will be returned 90 to the cooling medium for condensation through the suction created in the Venturi tube 7, but even under these conditions, the pressure in the vapor chamber, being contin- ually augmented by the vapor generation 95 at the cylinder walls and hot wetted surfaces, will be found to be materially in excess of that necessary to prevent a boiling condition of the cooling medium at the surface. This provides an excess vapor pressure which should be relieved in order to prevent too 100 great a head on the surface of the cooling medium. This excess vapor pressure may be readily utilized as auxiliary power, and in Figure 2 there is illustrated a pipe con- 105 nection with the vapor space 14 leading through a governor 26 and beyond the gov- ernor to a prime mover 27 with the exhaust from the latter returning through a pipe 28 to the condenser 4.

Under these circumstances, the condenser 110 should be provided with means whereby its communication with the vapor space may be governed or entirely cut off at will, such for example as illustrated at 29 in Fig. 2. The governor 26 is designed to permit the pas- 115 sage therebeyond of the saturated vapor pressure or steam in excess of the pressure required to balance the boiling condition of the cooling medium, and this excess pressure is utilized to operate the prime mover 27 for 120 the development of power for any purpose. Therefore, the excess vapor pressure is utilized for work or may be used for external heating instead of being dissipated to the atmosphere through an ordinary relief valve. 125

The system, therefore, through simple manual controls, may be used to maintain an effective working temperature of the engine at any practical degree within the limits of the heat generated by the combus- 130

tion charge, with the larger number of heat units retained in the charge for work, through the possibility of the dissipation through the cylinder walls of but a small number of such heat units, while the heat passing through is absorbed by the cooling medium and its energy used in the generation of additional vapor. It is apparent that the combustion charge in its expansive duration is of materially increased effectiveness as compared with the ordinary combustion charge, for being initiated and maintained at a higher degree of heat, naturally the effectiveness of this heat degree will remain within the cylinder a greater length of time and therefore be effective for a greater ratio of expansion throughout a longer stroke before reaching the normal heat equalization at which it loses its power.

20 The improved system, then, operates in a cycle closed against the admission of air. The heat dissipation of the cooling medium is so controlled as to be in exact accordance with the heat generated at the surface to be cooled, the dissipation increasing as this heat increases and decreasing as the heat decreases; this rate of heat dissipation being directly controlled through the speed of the engine. The system is entirely automatic 25 and being closed against the admission of air, causes substantially no loss of cooling medium, whether such cooling medium contain as a constituent part the usual volatile anti-freeze materials or not.

30 35 This application is a continuation in part of my application filed November 19, 1923, Serial No. 675,633, and my application filed July 10, 1924, Serial No. 725,146.

What is claimed to be new is:

• 1. A method of providing a cooling system for internal combustion engines, consisting in circulating a cooling medium in a system permanently closed against the admission of air, and varying the specific heat 30 of the medium from a predetermined minimum to a predetermined maximum as the engine heat is increasing from substantially atmospheric temperature to the normal operating temperature of the engine.

50 55 2. A method of providing a cooling system for internal combustion engines, consisting in circulating a cooling medium in a system permanently closed against the admission of air, maintaining said medium in an aerated condition during the initial operation of the engine, and thereafter circulating said medium in a deaerated condition for heat dissipation of excess engine heat.

60 65 3. A method of providing a cooling system for internal combustion engines, consisting in circulating a cooling medium in a system permanently closed against the admission of air, providing for the collection of vapor incident to the heating of the medium, condensing said vapor for return to the cooling

medium, and controlling the rate of condensation by the speed of the engine.

4. A method of providing a cooling system for internal combustion engines, consisting in circulating a cooling medium in a system permanently closed against the admission of air, condensing the vapor of such cooling medium, delivering the condensate to the circulating medium through the suction of such medium under circulation, and varying the suction in accordance with the speed of the engine.

5. A method of providing a cooling system for internal combustion engines, consisting in mechanically circulating a cooling medium in a system permanently closed against the admission of air, and providing for a mass flow of such medium to such mechanical circulating means dependent upon a variable pressure head above its surface with the pressure head controlled by variable suction created by the velocity of the fluid below its surface.

6. The herein-described method of providing a cooling system for internal combustion engines, consisting in mechanically circulating a cooling medium in a system permanently closed against the admission of air, with the rate of mass flow of said medium to such mechanical circulating means dependent upon a pressure head of a saturated vapor above its surface, with such pressure head varied by a suction created by the velocity of flow below its surface.

7. A method of providing a cooling system for internal combustion engines, consisting in mechanically circulating a cooling medium in a system permanently closed against the admission of air, utilizing the vapor of the medium as a pressure head on the surface of the medium, relieving the pressure of such head in accordance with the engine speed, and increasing the mass flow of the cooling medium to the mechanical circulating means through such unrelieved pressure head.

8. A method of providing a cooling system for internal combustion engines, consisting in mechanically circulating a cooling medium in a system permanently closed against the admission of air, and providing for the condensation of the vapor of such cooling medium and the return of the condensate to the cooling medium at a rate controlled by the circulation of the medium, the negative or positive pressure of said vapor as resulting from the rate of condensation correspondingly affecting the mass flow of the cooling medium to the mechanical circulating means.

9. A method of providing a cooling system for internal combustion engines, consisting in mechanically circulating a cooling medium in a system permanently closed against the admission of air, subjecting the vapor of the cooling medium to condensation and suction with the degree of suction controlled by the

circulation of the cooling medium, the suction being sufficient under a low rate of vaporization to exert a negative influence on the mass flow of cooling medium in the direction of its circulation, whereby to retard such mass flow to permit an increased heat absorption of the cooling medium in a given time.

10. A method of providing a cooling system for internal combustion engines, consisting in circulating a cooling medium in a system permanently closed against the admission of air, collecting the vapors of the medium on the surface thereof, subjecting such vapors to a suction generated by and in proportion to the rate of circulation of the cooling medium, condensing the vapors while under suction, and varying the heat dissipation incident to the conversion into vapor in accordance with the rate of circulation of the cooling medium.

11. A method of providing a cooling system for internal combustion engines, consisting in circulating a deaerated cooling medium in a system permanently closed against the admission of air, mechanically controlling the circulation, and utilizing the excess vapor pressure generated by the cooling medium under retarded circulation as a surface pressure on the medium.

30 12. A method of providing a cooling system for internal combustion engines, consisting in circulating a deaerated cooling medium in a system permanently closed against the admission of air, mechanically controlling the circulation, and utilizing the excess vapor pressure generated by the cooling medium under retarded circulation as a surface pressure on the medium, the excess vapor pressure providing in part an independent power source.

45 13. An apparatus for use as a cooling system for internal combustion engines, including a water reservoir, circulating pipes communicating with said reservoir, means for causing a water circulation through said pipes and reservoir and into contact with the surfaces to be cooled, a condenser for condensing the vapor generated in the heating of the cooling medium, and means for returning the condensed vapor to the system under the power generated by the circulation of the cooling medium, said system as an entirety being permanently closed against the admission of air.

55 14. A cooling system for internal combustion engines including a water reservoir, circulating pipes leading to and from the surface to be cooled and in communication with the reservoir, means for compelling a circulation of the cooling medium between the reservoir and surface to be cooled, means for collecting and condensing the vapor generated in the heating of the cooling medium, and a Venturi tube arranged in the path of the circulating cooling medium and into

which the condensed vapor is delivered, said system being permanently closed against the admission of external air.

15. A cooling system for internal combustion engines including a radiator, cylinder jacket, pipes leading from the upper and lower ends of the radiator to the cylinder jacket to provide a circulating system, a pump in said system, a Venturi tube in the pipe leading from the bottom of the radiator, a condenser communicating with the space in the radiator above the level of the cooling medium, a pipe leading from the condenser and opening into the Venturi tube at the point of restricted area therein, and a valve arranged between the radiator and Venturi tube to control the rate of circulation.

16. A method of providing a cooling system for internal combustion engines, consisting in circulating a cooling medium in a system permanently closed against the admission of air, condensing the vapor of such cooling medium, delivering the condensate to the circulating medium through the suction of such medium under circulation, and varying the suction by the speed of the engine.

17. That method of providing a cooling system for internal combustion engines consisting in maintaining a circulation permanently closed against air admission, supplying a cooling medium consisting of a mixture of fluids having relatively different specific heats, and automatically varying the relative proportions of said fluids in the cooling medium in accordance with the variation in temperature of the engine parts to be cooled to thereby change the specific heat of the mixture.

18. That method of providing a cooling system for internal combustion engines consisting in maintaining a circulation permanently closed against air admission, supplying a cooling medium consisting of a mixture of fluids having relatively different specific heats and specific gravities, and varying the specific heat of the mixture proportionally in accordance with the variation in temperature of the engine parts to be cooled by changing the relative proportions of the fluids forming such mixture.

19. That method of cooling the cylinders and adjacent parts of an internal combustion engine which consists in providing the circulation of a cooling medium consisting of a mixture of a plurality of fluids having different specific heats in a system closed to the admission of air, maintaining the mixture during the circulation of the cooling medium while the parts to be cooled remain below a predetermined temperature, and permanently discarding from the system the fluid of least specific heat when the circulating medium exceeds such predetermined temperature.

through the heat absorbed from the engine parts being cooled.

20. That method of providing a cooling system for internal combustion engines consisting in circulating a cooling medium consisting of a mixture of water and excess air to reduce the heat absorptive properties of the mixture in a system closed to the admission of air, maintaining the mixture to a predetermined heat degree thereof, and thereafter permanently discarding from the system the excess air from the mixture in proportion to the increasing heat of the engine parts to be cooled.

21. That method of operating the cooling system of an internal combustion engine having a system closed against the admission of air which consists of circulating a mixture of water and excess air, maintaining the mixture until the heat degree thereof incident to the heat absorbed from the engine parts tends to a vaporization of the water, and thereafter utilizing the pressure of said vapor to displace the excess air of the mixture to thereby increase the specific heat of the cooling medium.

22. That method of operating the cooling system of an internal combustion engine consisting in circulating a cooling medium made up of a mixture of two fluids in a system closed against the admission of air, one of lower specific heat than the other, maintaining the mixture as a cooling medium up to a degree of heat of the mixture tending to produce vaporization of one of the fluids, and thereafter discarding the fluid of least specific heat from the mixture to thereby increase the specific heat of the cooling medium.

23. That method of operating the cooling system of an internal combustion engine having a system closed against the admission of air which consists of circulating a cooling medium made up of a mixture of two fluids, one of lower specific heat than the other, maintaining the mixture as a cooling medium up to a degree of heat of the mixture tending to produce vaporization of one of the fluids, and thereafter utilizing the pressure of the vapor generated from the fluid of greater specific heat to separate from the cooling medium the fluid of less specific heat.

24. That method of operating the cooling system of an internal combustion engine consisting in circulating in a system closed against the admission of air a cooling medium made up of a mixture of two fluids, one of lower specific heat than the other, maintaining the mixture as a cooling medium up to a degree of heat of the mixture tending to produce vaporization of one of the fluids, and thereafter utilizing the pressure of the vapor generated from the fluid of greater specific heat to separate from the cooling medium the fluid of less specific heat, the separa-

tion being in proportion to the vapor generation of the fluid of greater specific heat.

25. The method of cooling an internal combustion engine having a forced circulation in a system permanently closed to admission of air consisting of circulating a mixture of water and excess air, maintaining such mixture until the heat degree thereof due to combustion heat absorption tends to vaporize the water of the mixture, then utilizing the kinetic energy from the condensation of said vapor to increase the specific heat of said cooling mixture as well as to accelerate its circulation flow.

26. A cooling system for internal combustion engines including a circulatory system permanently closed against the admission of air, means whereby the air initially in the system is circulated with the cooling fluid as an air and water emulsion, and means by which said air on reaching a predetermined pressure is expelled from the system to thereafter maintain the cooling medium in a de-aerated condition.

27. A cooling system for internal combustion engines including a circulating system having a reservoir and power circulating means, the normal level of the cooling fluid in the reservoir providing a vapor chamber above such fluid for the collection of air and vapor, a condenser in communication with such chamber and with the circulating system beyond the reservoir, the circulation of the cooling medium beyond the reservoir withdrawing the condensate of such condenser for mixture with the cooling medium in accordance with the speed of circulation of the latter.

In testimony whereof I affix my signature.
